UNITED STATES PATENT OFFICE.

JOSEPH PAVELKA, OF ST. LOUIS, MISSOURI.

BUTTON-STAPLING MACHINE.

1,356,219.

Specification of Letters Patent. Patented Oct. 19, 1920.

Application filed August 6, 1918. Serial No. 248,552.

To all whom it may concern:

Be it known that I, JOSEPH PAVELKA, a citizen of the United States, residing at St. Louis, Missouri, have invented a certain new and useful Improvement in Button-Stapling Machines, of which the following is a full, clear, and exact description, such as will enable others skilled in the art to which it appertains to make and use the same, reference being had to the accompanying drawings, forming part of this specification.

My invention relates generally to shoe machinery and more particularly to a button attaching machine, the principal object of my invention being to provide a relatively simple mechanism wherein a button and section of wire are fed into proper association, the wire being bent into a staple in engagement with the eye of the button, and said staple carrying the button being driven through and clenched on to the work.

Further objects of my invention are, to provide a stapling machine of the class described which, by virtue of the small number and simplicity of parts required, will be economical in cost of manufacture, and likewise economical in cost of repairs and renewal of worn or broken parts; to provide improved means for delivering the buttons from the hopper or container to the chute which carries said buttons to the anvil and wire feeding mechanism; to provide means for enabling the rapid interchange of buttons; and further, to provide a machine which is durable in construction and which will rapidly and efficiently perform its intended functions.

With the foregoing and other objects in view, my invention consists in certain novel features of construction and arrangement of parts, hereinafter more fully described and claimed, and illustrated in the accompanying drawings, in which—

Figure 1 is an elevational view of a button setting machine of my improved construction, parts thereof being in section.

Fig. 2 is a front elevational view of the machine with parts broken away and a portion of the button hopper or container in section.

Fig. 3 is an enlarged plan view of the anvil and adjacent mechanism, with parts broken away and in section.

Fig. 4 is an enlarged horizontal section taken approximately on the line 4—4 of Fig. 1.

Figs. 5 and 6 are elevational views of parts of the staple forming and driving means and showing the same in different positions.

Fig. 7 is an enlarged detail section taken approximately on the line 7—7 of Fig. 2.

Figs. 8, 9, 10 and 11 are elevational views partly in section and showing different positions of the staple forming and driving means.

Fig. 12 is an enlarged vertical section taken approximately on the line 12—12 of Fig. 2.

Fig. 13 is an elevational view of a combined mutilated gear and cam member utilized in my improved machine.

Figs. 14 and 15 are perspective views of the parts comprising the staple forming and driving means.

Fig. 16 is a perspective view of the member utilized for carrying the buttons from the end of the button chute to the staple forming and driving means.

Fig. 17 is an elevational view of the button feeding member.

Fig. 18 is a vertical section taken approximately on the line 18—18 of Fig. 2.

Fig. 19 is a vertical section taken approximately on the line 19—19 of Fig. 18.

Fig. 20 is an enlarged detail section taken approximately on the line 20—20 of Fig. 3.

Referring by numerals to the accompanying drawings which illustrate a practical embodiment of my invention, 10 designates a horizontally disposed plate or table which is supported at a suitable elevation, preferably by means of legs 11 or a suitable framework, and fixed to said table and projecting upwardly therefrom, is a casting 12 which forms the main supporting frame for the operating parts of the machine. This casting is provided with various bearings, supporting arms and brackets which are hereinafter more specifically described. An up-

60

85

100

wardly projecting portion 13 at the front of this casting 12 serves as an anvil and work support, the upper face of said anvil being provided with a pair of alined transversely disposed grooves 14 which receive the ends of the staple after the same is formed and guides said ends upwardly to clench the work. (See Fig. 6.)

Formed in casting 12 immediately to the rear of the anvil 13 are bearings 15, the same being spaced apart a suitable distance and serving as supports for the end of a horizontally disposed shaft 16. Projecting upwardly from the righthand one of these bearings is a post or bracket 17, the same serving as a support for a part of the wire feeding means.

Formed in the casting 12 to the rear of bearings 15 is a pair of spaced bearings 18 which serve as a support for the ends of a transversely disposed shaft 19, and formed integral with and projecting outwardly from the casting adjacent to the righthand one of these bearings is a horizontally disposed bracket 20, the same serving as a support for a spool 21 of wire, and which latter is fed to the machine and formed into button attaching staples.

Formed integral with the casting adjacent the lefthand one of bearings 18 is an upwardly projecting bracket or standard 22 which serves as a support for the button chute. Formed integral with the rear portion of the casting 12 and projecting upwardly therefrom is a pair of arms or brackets 23, the upper ends thereof being provided with bearings for a horizontally disposed shaft 24. These arms 23 also serve as a support for the button container, hereinafter more fully described.

Arranged between the lower portions of arms 23 is a vertically disposed bearing 25 and arranged to move freely therethrough is a rack bar 26. Pivotally connected to the lower end of this rack bar is the upper end of a connecting rod 27, the lower end of the latter being pivotally connected to the rear portion of a pedal lever 28, the rear end of the latter being pivotally connected to the lower portion of the supporting framework for table 10. Connected to this lever 28 in front of the connecting rod 27 is the lower end of a retractile spring 29, the upper end of which is connected to a suitable part of the supporting framework 11 and said spring normally holding the forward end of lever 28 in elevated position.

Loosely mounted on shaft 19 is a mutilated pinion 30, the teeth of which mesh with the teeth of rack 26 and formed integral with or fixed to the right hand side face of said pinion is an outwardly projecting flange 31, the outer face of which is inclined relative to a vertical plane. Formed

integral with or fixed to pinion 30 and on the lefthand side thereof is a mutilated pinion 32, and formed integral with or fixed to this pinion and on the lefthand side thereof is a cam disk 33 having formed on its periphery a relatively short lug or projection 34 and a longer lug or projection 35.

Loosely seated in one of the teeth of pinion 30 and at the end of the elongated opening or space between said teeth is a pin 36 provided on one end with a head 37 and interposed between this head and the tooth in which said pin is seated is a compression spring 38. This spring-held pin performs the functions of a yielding tooth in a manner hereinafter more fully described.

Loosely mounted on shaft 16 is a pair of segmental plates 39, the same being rigidly connected near their outer edges by a transversely disposed web 40. One of these plates is provided with a series of teeth 41 which mesh with the teeth of pinion 30. Formed in the front faces of the plates 39 and near their outer edges are alined horizontally disposed wire receiving notches 42 and formed on the inner or adjacent faces of said plates 39 and leading upwardly from these notches 42 are grooves 43 which latter receive the legs of the staple after the same has been formed. (See Fig. 5).

Seated in the rear portion of the lefthand one of plates 39 is an outwardly projecting pin 44 and pivotally arranged on the outer end thereof is a horizontally disposed spring-held detent 45, the same being provided on its forward end with hook 46. Loosely arranged between plates 39 is a plate 47 in which is formed a slot 48 through which shaft 16 passes, and formed on the lower portion of this plate is a series of teeth 49 which are adapted to engage with the teeth of mutilated pinion 32.

One end of a retractile spring 50 is secured to the lower end of this plate 47, the opposite end of said spring being secured to the lower portion of casting 12. Projecting outwardly from the lefthand side of the lower portion of plate 47 is a pin 51. Pivotally mounted on the lefthand side of bearing 25 is a forwardly projecting arm 52 in the forward end of which is formed a substantially inverted L-shaped slot 53, which slot receives pin 51.

Interposed between the base of casting 12 and the forward end of this arm 52 is a compression spring 54 which normally maintains the forward end of arm 52 in an elevated position with pin 51 occupying the lower end of the vertical leg of slot 53. (See Fig. 12).

The arm 52 lies immediately beneath disk 33 and formed on the upper edge of said arm is an upwardly presented lug 55 which is adapted to be engaged by the lugs 34 and 130

35 on said disk 33, and formed in said arm immediately in front of this lug 55 is a recess 56.

Formed integral with the upper portion of plate 47 is an upwardly projecting lug 57 which performs the functions of a hammer or pressure member to force the staple through the work and to cause the legs of said staple to clench against the underside 10 of the work by reason of contact of the anvil 13, and formed in the front upper corner of this lug is a notch 58 which receives the eye of the button while the staple is being driven through and clenched behind 15 the work, as illustrated in Fig. 6.

Formed in the front edge of the lug 57 to the sides of this notch or recess 58 are aligned horizontally disposed grooves 59 which are adapted to coincide with grooves 20 42 in plates 39 when the staple is being forced through and clenched upon the work. Formed in the upper rear corner of the lug 57 is a button eye-receiving notch 60, the same being intersected by a transversely disposed 25 wire receiving aperture 61.

Removably positioned on standard 22 is an inclined chute 62 of sufficient size to receive the bodies of ordinary shoe buttons, and formed in the bottom of this chute is 30 a longitudinally disposed slot 63 through which the eyes of the buttons project. The slotted bottom of this chute extends downwardly and outwardly and terminates at a point immediately above the path of travel 35 of the upper edges of plates 39 and the outer end of hammer 57. (See Fig. 7). Secured to the lower end of chute 62 and projecting downwardly over a part of the projecting bottom of said chute is a relatively light 40 spring 64, the forward end of which is curved downwardly and said spring serving as a yielding finger for controlling the feed or movement of the row of buttons downwardly through the chute and onto the outer 45 end of the lower portion of said chute and in which latter position the buttons are successively engaged by the end of hammer 57. (See Fig. 7). The lower portion of this 50 spring 64 is provided with a longitudinally disposed slot 64a.

The means utilized for transferring the lowermost one of the buttons within the chute from its position behind the curved outer end of spring 64 to the extreme outer 55 end of the lower portion of said chute includes a plate 65 provided with a slot 66 which receives shaft 16 and secured to the lower end of this plate is one end of a retractile spring 67, the opposite end of which 60 is secured to the lower portion of casting 12. This spring normally acts to draw the plate 65 downward and in such position the shaft 16 occupies the upper end of slot 66. Projecting upwardly from the rear portion of 65 plate 65 is an angular arm 68, a part of the

upper portion of which is bent laterally as designated by 69 and said laterally bent portion overlying the lefthand one of plates 39. This laterally bent portion terminates in a depending button engaging hook 70, the 70 same being provided with a curved lower edge, and this hook operates through the lower portion of the slot 64a in the spring 64.

Formed on the rear upper edge of plate 65 is an outwardly projecting flange 71 75 which is adapted to be engaged by the hook 46 on the end of detent 45. (See Fig. 16). Projecting outwardly from the lefthand side of plate 65 is a pin 72 and pivotally mounted upon a pin 73 which is seated in an adjacent 80 part of the bracket 17 is a relatively short dog 74, the free end of which is normally held in depressed position by a suitable spring 75, the same bearing upon a pin 76 which projects outwardly from said dog. 85 Seated in the lower portion of post 22 is a screw 75a against which the rear end of detent 45 is adapted to engage when the latter is at its rearward limit of movement.

Under normal conditions, pin 72 is positioned beneath the pivoted end of the dog 74 as illustrated in Fig. 17. This dog is for the purpose of elevating plate 65 in order to position the hook 70 over the lowermost one of the buttons in chute 62 and transfer 95 said button into position on the hammer and staple forming means.

Supported between the upper portions of the arms 23 is a suitable button receptacle or hopper 77, a portion 78, preferably at the top thereof, being constructed of transparent material such as glass or celluloid, and formed in the front wall of this receptacle is an opening 79 into which extends the upper end of button chute 62. The button chute is detachably connected to the receptacle in any suitable manner, preferably by means of a pin 80 which is loosely seated in a recess or aperture formed in a part of 100 said receptacle.

The parts of the slotted bottom of the chute 62 are spread apart within the button receptacle to form button guiding plates 81 and extending transversely across the receptacle above these plates is a rail 82, the 105 underside of the center of which is notched as designated by 83 in order to permit the heads of buttons to enter the slot in the bottom of the chute.

Carried by shaft 24 within the receptacle 120 77 is an ordinary horse-shoe magnet 84, the greater portions of the legs of which are covered by a suitable shield 85 of insulation, thereby exposing only the ends of the legs of said magnet.

During operation or movement of the magnet, the outer ends of its legs travel in a path immediately beneath the slot between the guiding plates 81 and likewise immediately beneath notch 83 in deflecting bar 130

82. Projecting from the rear end of magnet 84 is a finger 86 which serves as a stir for the buttons contained in the lower portion of receptacle 77.

5 Fixed on the righthand end of shaft 24 is a pinion 87 which is engaged by the teeth of a rack bar 88, the latter being formed integral with or fixed to the upper end of rack bar 26.

10 By reason of the fact that pinion 87 is arranged outside the adjacent arm 23, the rack bar 88 is offset laterally relative to the rack bar 26.

15 Pivottally mounted on bracket 20 is a horizontally disposed arm 89, the outer end of which is adapted to receive the strand of staple forming wire which is carried upon spool 21, and pivottally mounted on the outer end of said arm is a pivottally mounted 20 spring-pressed wire gripping member 90.

A coiled spring 89', one end of which is secured to the arm 89 the other end being secured to the bracket 17, is provided to control the arm 89 as hereinafter described.

25 Formed in the righthand one of brackets 17 is an aperture 91 through which the staple forming wire is adapted to feed, and pivottally mounted above said aperture is a spring-pressed wire gripping member 92.

30 (See Fig. 20.) The operation of my improved button setting machine is as follows:

Under normal conditions, or with the machine ready for operation, the various parts

35 occupy the positions illustrated in Figs. 1, 3 and 7, with the eye of a button occupying the notch 60 in hammer 57 and the end portion of the stapling wire seated in the notches 42 and passing through the eye of 40 said button.

The work which is to receive the buttons is placed on top of anvil 13 and the forward end of lever 28 is pedally engaged and moved downward, such action necessarily 45 imparting downward movement to rack bars 26 and 88. The teeth of rack bar 26 engaging with the teeth of pinion 30 rotates same on shaft 19 and this rotary movement is transmitted to plates 39 inasmuch 50 as the teeth of said pinion 30 are in engagement with teeth 41 on one of said plates.

The first movement imparted to the plates 55 39 cuts the section of the wire occupying the notches 42 as illustrated in Fig. 4, by a shearing action between the outer edge of the righthand one of plates 39 and adjacent edge of the righthand post or standard 17. Segmental plates continue to move forwardly and downwardly toward the anvil 60 during which time plate 47 remains stationary, inasmuch as mutilated pinion 32 is not yet in engagement with the teeth 49 on said plate 47, and said plate is held in its stationary position by pin 51 in the lower end 65 of slot 53. This movement of plates 39 past

stationary hammer 57 on plate 47 bends the end portions of the severed section of wire into positions parallel with each other, thereby forming the legs of the staple and which legs occupy the grooves 43 on the 70 inner faces of said plates 39. (See Fig. 5.) Immediately following this action, lug 34 on disk 33 engages lug 55 on arm 52, thereby swinging the free end thereof downward, with the result that the hook above slot 53 75 engages on top of pin 51, bearing downwardly thereupon and immediately pulling plate 47 downward into the position as illustrated in Fig. 9, with the notch or recess 60 disengaged from the eye of the button. 80 After lug 34 passes lug 55 and enters notch 56, arm 52 will move upward under the influence of spring 54, thereby assuming the position illustrated in Fig. 10 and at this instant, lug 35 engages lug 55 on arm 52 85 and moves the same downward until pin 51 occupies the horizontal or upper right portion of slot 53. With the parts thus positioned, the hammer 57 is in position immediately to the rear of notches 42 and grooves 43, the latter being occupied by the legs of the staple. 90 At this instant, the first tooth of mutilated pinion 32 engages the teeth 49 of plate 47, and the latter is rotated upon shaft 16 independently of plates 39, with the result 95 that the top of the staple is engaged and said staple carrying the button is forced downwardly from its position between the front edges of plates 39.

During the staple driving action, pin 51 100 will travel through the upper portion of slot 53, plate 42 being held in depressed position by lug 35 engaging lug 55.

The legs of the staple will be forced through the work and the ends of said legs 105 bearing in the grooves 14 will be turned upwardly toward each other and thereby be firmly clenched against the underside of the work. It will be understood that all of the movements just described take place in 110 rapid succession as the lever 28 and parts connected thereto are moved downward.

After the front edges of the segmental plates 39 are brought into engagement with the upper surface of the work lying on the 115 anvil 13, the head of pin 36 bears against the outer face of the lower one of the teeth 41 and upon the continued rotary movement of pinion 30, pin 36 will be forced through the tooth on which it is mounted 120 and spring 38 will be compressed, such action being provided in order to compensate for varying thicknesses of material placed on the anvil and to which the buttons are attached.

As disk 30 is rotated by the downward movement of rack 26 as just described, flange 31 having the inclined outer face will bear against the inner edge of arm 89 and swing said arm outwardly during which 130

movement gripping member 90 will ride over the wire passing through the end of said swinging arm, and upon the return movement of pinion 30, arm 89 will swing inward under the action of spring 89', thereby feeding the required length of wire through grooves 42 and 61 and through the eye of the button which occupies the recess 60. The spring-pressed gripping member 92 holds the wire against being pulled outwardly as arm 89 is thus swung outwardly.

Obviously the downward movement of rack 26 imparts reverse rotary movement to pinion 30 and the various parts actuated by said pinion and the associated pinion and disk 32 will be returned to their normal positions, as illustrated in Fig. 7.

Under normal conditions, the rear end of detent 45 bearing against screw 75^a holds said detent in an inclined position, as illustrated in Fig. 3 with the hook 46 disengaged from flange 71. During the forward movement of plates 39, one of which carries detent 45, the latter will swing into a position approximately parallel with the planes occupied by said plates, as illustrated in Fig. 14 and upon the return of the plates 39 to their normal positions, hook 46 will engage flange 71, thereby rocking plate 65 upon the shaft 16 so as to swing the button engaging hook 70 on the upper end of said plate rearwardly or to a position to engage immediately over the lowermost one of the buttons in the chute 62 and which button is positioned against the curved lower end of spring 64. Simultaneous with this rearward swinging movement of plate 65, said plate will be elevated by the movement of pin 76 riding over dog 74, which latter is pivoted to a fixed part of the frame and when hook 70 has engaged the lowermost one of the buttons, the rear end of detent 45 will come in contact with pin 75^a, thereby throwing the forward end of said detent outwardly, consequently disengaging hook 46 from flange 71, and plate 65 and parts carried thereby will instantly ride to their normal positions under the influence of spring 67, and consequently carrying the lowermost one of the buttons downwardly onto the projecting bottom portion of the chute and with the eye of said button seated in notch 60.

During the forward swinging movement of plate 65 pin 72 will ride beneath dog 74 as illustrated in Fig. 17, consequently raising the forward end of said dog, but on the rearward movement of the plate, said pin will ride over the dog with the result that said plate will be simultaneously elevated with its rearward swinging movement. Thus on the upward movement of rack bar 26 and return of the various parts to their normal positions, a button will be placed in proper position on the carrying means

with the eye of said button in the recess 60 and immediately after the button is thus positioned, arm 89 will ride off the flange 31 and the end of the wire will be fed through the eye of the button, thus completing the cycle of operations.

As rack bar 26 is drawn downward, as heretofore described, rack bar 88 will be likewise drawn downward, thereby imparting rotary movement to pinion 87 and shaft 24, with the result that the magnet 84 will be partially rotated within the button container and the eyes of the buttons being of metal will be attracted and held upon the ends of the legs of said magnet. As the magnet revolves in the opposite direction within the housing, the engaged buttons with the body portions uppermost will be moved between the curved plates 81 forming the upper portion of the bottom of the button chute and the heads of said buttons will pass beneath the notch 83 of deflector 82. Thus, with each upward movement of the rack bar, one or more buttons will be delivered in proper position into the upper end of the button chute.

In the event that it is desired to attach a certain size or style of button into work such as a pair of shoes, the button chute 62 can be readily disengaged from the button receptacle and from the support 22, and the special style of buttons may be manually fed into the upper end of the chute.

Thus it will be seen that I have produced a button stapling machine which is composed of relatively few parts, the same coöperating to act positively, rapidly and efficiently to perform their intended functions and achieving the desired results.

While the various parts constituting my complete machine have been described somewhat particularly, it will be understood that the structural details are capable of considerable variation within the spirit and scope of the appended claims.

I claim:

1. In a button stapling machine, staple forming means comprising a rotatable divided member provided with wire receiving grooves, and a member loosely mounted within said divided member, said loosely mounted member capable of rotary movement and sliding movement independently of the divided member, and said loosely mounted member being provided with wire receiving grooves.

2. In a button stapling machine, staple forming means comprising a rotatable divided member provided with wire receiving grooves, and a member loosely mounted within said divided member, said loosely mounted member capable of rotary movement and sliding movement independently of the divided member, and said loosely mounted member being provided with wire receiving grooves.

receiving grooves, and a button eye-receiving recess.

3. In a button stapling machine, staple forming means comprising a rotatable divided member provided with wire receiving grooves, a member loosely mounted within said divided member, said loosely mounted member capable of rotary movement and sliding movement independently of the divided member, and said loosely mounted member being provided with wire receiving grooves, and means for imparting rotary movement to said divided member and loosely mounted member.
- 15 4. In a button stapling machine, staple forming means comprising a rotatable divided member provided with wire receiving grooves, a member loosely mounted within said divided member, said loosely mounted member capable of rotary movement and sliding movement independently of the divided member, and said loosely mounted member being provided with wire receiving grooves, means for imparting rotary movement to said divided member and loosely mounted member, and means for imparting sliding movement to said loosely mounted member simultaneous with its rotary movement.
- 20 5. In a machine of the class described, the combination with wire feeding means and button feeding means, of staple forming and driving means comprising a divided member provided with wire receiving grooves, and an independently operating driver coöperating with said divided member for forming the staple and driving the legs thereof through the work.
- 25 6. In a staple setting machine, the combination with wire feeding means, staple forming and setting means, and button transferring means, of a one-piece rotatably mounted operating member comprising mutilated pinions adapted to actuate the staple

forming and setting means, a cam for actuating the wire feeding means, and a cam for actuating the button transferring means.

7. In a button stapling machine, staple forming means comprising a rotatable divided member provided with wire receiving grooves, a member loosely mounted within said divided member provided with a series of teeth and a striking lug or hammer, said loosely mounted member capable of rotary movement and sliding movement independently of the divided member, and the loosely mounted member having wire receiving grooves on two surfaces, means for imparting rotary movement to said members, and means for imparting sliding movement to said loosely mounted member simultaneous with its rotary movement.

8. In a button stapling machine, a combined button carrier and staple forming means, a button feeding chute, means for transferring a button onto said carrier from the chute, an anvil against which said staple forming means is adapted to impinge with rotation in a given direction, and a wire feeding mechanism adapted to feed the wire to the next succeeding button when said staple forming means is rotated.

9. In a button stapling machine, staple forming means comprising a rotatable divided member provided with wire receiving grooves, a member loosely mounted within said member, reciprocally and rotatably movable and provided with a hammer, an anvil against which said hammer is adapted to impinge, means for imparting rotary movement to said staple forming means and member, means for imparting reciprocating movement to said member, and means for restoring the parts to normal position.

In testimony whereof I hereunto affix my signature this 3d day of August, 1918.

JOSEPH PAVELKA.
